UNITED STATES PATENT OFFICE

2,209,819

ELECTRIC DISCHARGE APPARATUS

Kenneth H. Kingdon, Schenectady, N. Y., assignor to General Electric Company, a corporation of New York

Application July 29, 1939, Serial No. 287,341

4 Claims. (Cl. 175—354)

The present invention relates to improvements in controllable arc-discharge apparatus and has for its primary object the provision of apparatus of this character which is adapted for use at 5 high voltages.

In connection with the attainment of the above-stated object, an important feature of the invention consists in the inclusion in a grid-controlled arc-discharge apparatus of one or 10 more intermediate electrode elements between the control grid and the anode for subdividing the voltage drop between them in such fashion as to lessen the possibility of undesired breakdown.

15 Another important feature, ancillary to the above, involves the use of means for maintaining a potential relationship between the various intermediate electrodes of such character as to decrease the time interval which must elapse 20 between the end of one conducting period of the apparatus and the instant when a discharge-favoring potential may again be applied to such apparatus without the immediate occurrence of breakdown.

25 The aspects of the invention which I desire to protect herein are pointed out in the appended claims. The invention itself, together with further objects and advantages thereof, may best be understood by reference to the following de-

30 scription taken in connection with the drawings in which Fig. 1 comprises a sectional view of a discharge device embodying the invention, together with suitable circuit connections for the same; Fig. 2 shows diagrammatically the circuit 35 connections of Fig. 1, and Fig. 3 illustrates an inverter circuit in which the invention is applied.

For convenience in exposition the elements of the invention will first be described briefly without detailed reference to function. Their cooperative relationship then will be explained in connection with a particular utilization circuit.

Referring particularly to Fig. 1, there is shown an elongated discharge envelope comprising, for 45 example, a cylindrical metal portion 10 which is closed at its upper end by means of a transverse header 11 bolted thereto and which is joined at its lower end to a smaller cathode-containing portion 12. The part 12 is insulated 50 from the main body of the envelope by means of an insulator 13 and is united to the cylinder 10 by means of a bolted joint, indicated at 15. The lateral walls of the envelope are cooled by means of a cooling coil 16 which is arranged in good 55 thermal contact therewith. The envelope is also

provided with an exhaust duct 17 adapted for connection with an evacuating system.

At the upper end of the envelope there is provided an anode 19 which is supported by means of a hollow current-supply conductor 20. This 5 conductor is insulatingly joined to the envelope by means of a glass-to-metal seal indicated at 21.

The cathode of the device may consist of a solid electron emitter or, as shown, of a pool of 10 mercury 23 which serves also as a source of ionizable vapor during the operation of the apparatus. (A fixed gas, such as argon, may also be utilized in some cases as an auxiliary ionizing medium.) Above the cathode there is provided 15 a drip baffle 25 which has an annular trough-like peripheral portion adapted to receive mercury condensate running down the walls of the envelope and to prevent such condensate from streaming over the surface of the insulator 13. 20 Current may be supplied to the cathode by means of a heavy stud 27 secured to the bottom surface of the envelope part 12. For initiating a cathode-spot on the mercury surface, there is provided a make-alive electrode 28 of the immersion type; this being connected with a source of energizing potential (not shown) through a lead-in conductor 29.

Within the envelope and spaced from the cathode 23 there is arranged a keep-alive electrode 31 which is adapted to maintain a holding arc to the cathode surface. This is provided with current through a lead-in connection 32 which is protected from the effects of the arc stream by means of an insulating sheath 33.

35 Between the anode and cathode and in the vicinity of the former there are provided a plurality of grid electrodes, numbered 35 to 38 respectively. The grids 35 and 36 are so formed as substantially to enclose the anode and are 40 supported and energized by means of conductive cylinders 40 and 41 which respectively support them from metal lead-in rings indicated at 42 and 43. (The glass-to-metal seals by which the rings 42 and 43 are insulatingly mounted 45 are protected against bombardment by means of a series of shielding sleeves 44.) The grids 37 and 38 are cup-shaped and are insulatingly supported from the envelope header 11. They are respectively supplied with current through 50 lead-in seals 45 and 46. All of the grids are provided with perforations in those walls thereof which are directed toward the cathode, these 55 perforations being of sufficient size to permit passage of the discharge current.

In Fig. 1, and in another form in Fig. 2, there is shown a circuit with which the structure so far described may be employed to utilize the principles of my present invention. In this circuit, the anode 19 and the cathode 23 are intended to provide between them an intermittently conducting discharge path. To this end they are shown as being respectively connected to circuit conductors 48 and 49. These conductors in turn are to be connected to the terminals of an appropriate source of alternating or direct voltage depending on the conditions of use of the apparatus.

In order to control the conductivity of the discharge path the grid 37 is connected to one terminal of the secondary of a transformer 51 by means of which its potential relationship to the cathode 23 may be controlled. It will be understood that as long as the grid 37 is maintained negative with respect to the cathode, it will tend to prevent the occurrence of a discharge. On the other hand, when it is made positive with respect to the cathode it will tend to favor such a discharge. Its operation may be controlled in a desired manner by connecting the primary of the transformer 51 to a source of control potential (not shown) whose periodicity and phase are properly related to those of the anode-cathode potential. Transient influences, which might otherwise tend to produce sporadic firing of the tube, can be substantially eliminated by the use of a condenser 53 shunted across the transformer 51.

To facilitate the functioning of the control grid 37 there is provided in connection therewith an additional grid 38. The two grids referred to are connected to a common terminal of the transformer 51 through resistance elements 54 and 55 which are of different values. For the purposes of the present invention, the resistance 55 is preferably of the greater value so that current flow in the discharge space tends to maintain the grid 37 negative, with respect to the grid 38. The resulting establishment of a definite field between the grids 38 and 37 favors the creation of a completely closed ion sheath around the latter and thus increases its effectiveness in preventing a discharge.

The functioning of the grid 38 in this manner is due to the fact that it defines on the cathode side of grid 37 a segregated space from which ionization can disappear rapidly after cessation of conduction. In this way it serves to hasten the creation of a discharge-preventing, closed ion sheath around the grid 37.

In connection with the apparatus as so far described it will be seen that if the grid 37 is made equipotential with or negative to the cathode at a time when a high positive potential is applied to the anode 19, the entire anode-cathode voltage will appear between the anode and grid. If it is desired to use the apparatus at voltages as high as or above 100,000 volts, this consideration makes the avoidance of premature discharge a matter of some difficulty. Where such breakdown occurs, it is apt to be due to uneven distribution of the potential stress and the consequent occurrence of excessive gradients along some portion of the discharge path. In order to improve this situation, my invention employs means for subdividing the potential drop between the grid 37 and the anode 19. To this end, the grid 36 is connected through a resistance 58 to the midpoint of a potential divider, exemplified by a resistance 59. With this arrangement

the potential of the grid 36 is fixed at a value midway between the potentials of the cathode and anode and approximately midway between the potentials of the anode and the grid 37.

The successful functioning of the grid 36 as a voltage divider depends at least in part upon the substantial absence of ionization in the discharge space. To the extent that such ionization exists, there is a tendency for the grid 36 to be unable to prevent the main anode field from extending to the grid 37 and thus concentrating the potential stress across the ion sheath which surrounds that grid. My present invention includes as another important feature thereof the use of means for lessening the completeness of deionization required to permit effective subdivision of the interelectrode potential stress. The provision of such means has for its ultimate object the possibility of decreasing the time interval which must elapse between the end of one conducting period of the apparatus and the instant when a discharge-favoring potential may again be applied to the apparatus without the immediate occurrence of breakdown.

In the arrangement shown, the means referred to in the foregoing paragraph comprises the grid 35 and energizing connections therefor. Such connections include a transformer 62 which is shown as being energized from the same voltage source as the transformer 51 and which is so connected as to make the grid 35 negative with respect to the grid 36 whenever the grid 37 becomes negative with respect to the cathode 23. A resistor 63 is connected in circuit with the secondary of the transformer 62 to limit the current flow therethrough and a condenser 64 is connected across the transformer to diminish the effect of transient influences.

The occurrence of a definite potential field between the grids 35 and 36 during a period when residual ionization still exists in the discharge space appears to facilitate the creation of a closed positive ion sheath across the grid 35 and thus to hasten the moment when that grid is effective to prevent the penetration of the anode field into the space below it. When this condition is attained, the voltage in the discharge space is effectively divided between the region associated with the grid 35 and that associated with the grid 37. Furthermore, this condition is attained at a period appreciably earlier than would be possible without the provision of the elements referred to.

The principle of subdivision of stress may be carried to any desired length by providing additional grid pairs between the anode and the grid 37. The individual members of such grid pairs should, of course, be interrelated in the manner of the electrodes 35 and 36, and appropriately spaced connections to the potential divider 59 should be provided. In this latter connection, it will be understood that it is immaterial which member of the grid pair is connected to the divider as long as the point of connection is properly selected.

The invention described in the foregoing is of special utility in connection with apparatus desired to be employed for inversion purposes; that is to say, for the conversion of direct current to alternating current. A circuit illustrating this application is shown in Fig. 3 and serves further to explain the nature and utility of the invention.

Referring to Fig. 3 there are shown two sets of apparatus of the character described in Figs. 1 and 2, these sets being arranged in back-to-back relationship and being associated with additional

circuit means adapted to cause them to function conjointly as an inverter. In order to simplify the explanation, elements corresponding to parts already described have been similarly numbered, 5 and the numerals applied to the apparatus at the left-hand part of the drawing have been differentiated from those applied to the right-hand apparatus by the expedient of priming the numbers.

- 10 In the circuit illustrated, the anodes 19 and 19' are connected with the respective terminals of a transformer winding 67. The midpoint of this winding and the cathodes 23 and 23' of the respective discharge tubes are connected to the 15 terminals of a source of direct current potential as indicated at 68. The winding 67 is coupled to a secondary winding 69 which in turn is connected to an alternating current load device 70. Winding 67 is further shunted by means of a 20 condenser 72 which serves to facilitate commutation of the discharge between the two discharge tubes in a manner to be more fully explained in the following.

Inverter circuits of the general character of that described above are well known to the art so that their operation need not be elaborated herein. It may be stated generally that a conduction period through any one discharge tube is eventually terminated by the initiation of discharge 30 through the other tube. At the instant the discharge through a given tube ceases, the commutating condenser (e. g. condenser 72 of Fig. 3) drives the anode potential of such tube negative for a brief interval of time to permit deionization 35 to occur. The deionizing period must be made sufficiently long so that when positive potential is again applied to the anode, premature and undesired breakdown will not occur. The longer the 40 interval required for this purpose, the larger must be the capacity of the commutating condenser, so that for obvious reasons of economy it is desirable to make the necessary deionizing period as short as possible.

In order that the apparatus of Fig. 3 may serve the purpose referred to in the preceding paragraph, the excitation of the transformers 51 and 51' is synchronized with the voltage developed across the load device 70 to maintain a desired 45 and definite phase relationship between the potentials applied to the various grids and those applied between the respective anodes and cathodes. This may be done, for example, by connecting the transformers 51 and 51' to the 50 terminals of the transformer winding 69 through a phase shifter (not shown) or other means adapted to control phase relationship.

For the apparatus to operate in the intended 60 fashion, it is desirable that grid 35 shall be rendered negative with respect to grid 36 and that grid 37 shall be rendered negative with respect to cathode 23 at, or shortly before the time when positive potential is impressed on the anode 19. (Similarly, of course, the grids 35' and 37' should 65 be rendered negative before positive potential is applied to anode 19'.) The time interval by which the latter occurrence, namely, the application of positive potential to the anode elements, must be delayed is appreciably decreased by the use of the 70 grid combinations 35, 37 and 35', 37'; this being for the reason that the presence of these grids serves to facilitate the attainment of effective grid control even though the process of deionization 75 may be relatively far from completion. Thus the use of this aspect of my invention serves to reduce

the necessary size of the condenser 72 and thereby to diminish the cost of the inverter as a whole.

While I have described my invention in connection with a particular embodiment thereof, it will be understood that numerous modifications may be made therein by those skilled in the art without departing from the invention. I therefore, aim in the appended claims to cover all such variations as come within the true spirit and scope of the foregoing disclosure.

What I claim as new and desire to secure by Letters Patent of the United States, is:

1. In discharge apparatus of the type in which the discharge takes place through an ionizable medium, the combination which includes an anode, a cathode, a control grid between the anode and cathode, means for controlling the potential of the said grid in a manner tending to prevent the occurrence of a discharge between the anode and cathode during predetermined intervals, and 15 means for fixing the potential distribution between the grid and the anode, said means including a pair of intermediate electrodes, circuit connections for fixing the relationship between the potential of one electrode of said pair and the 20 potentials of the anode and cathode, and means for rendering the potential of the one of said electrodes which is nearer to the anode negative with respect to the other of said electrodes, at 25 least during a portion of the said predetermined 30 intervals.

2. High voltage apparatus comprising a discharge device having an anode, a cathode, an ionizable operating medium and at least three grid electrodes successively interposed between 35 the anode and cathode, means for applying a discharge-producing potential between the anode and cathode, means for applying a control potential to the one of said three grid electrodes which is nearest the cathode, means for fixing 40 the relationship between the potential of one of the other two grid electrodes and the potentials of the anode and cathode, and means effective 45 during periods of desired non-conduction of the device to render the one of said three electrodes which is nearest to the anode negative with respect to the central one of such electrodes.

3. In a discharge apparatus of the type in which conduction takes place through an ionizable medium, the combination which includes a discharge device having an anode and cathode, an energizing circuit connecting with said anode and cathode, the circuit being of such character that termination of one conducting period of the device is followed almost immediately by the application 50 between the anode and cathode of a potential favoring the renewal of conduction, a control grid between the anode and cathode, means for applying to the control grid a cyclically variable potential so phased as to inhibit renewal of 55 conduction by the device during predetermined intervals, and means for fixing the potential distribution between the control grid and the anode to facilitate the desired functioning of the former, said last-named means including a pair of intermediate electrodes, circuit connections for fixing 60 the relationship between the potential of one of said electrodes and the potentials of the anode and cathode, and means effective at least during the said predetermined intervals to render the 65 one of said electrodes nearer the anode negative with respect to the other electrode.

4. In a discharge apparatus of the type in which conduction takes place through an ionizable medium, the combination which includes a discharge 75

- device having an anode and cathode, an energizing circuit connecting with said anode and cathode, the circuit being of such character that termination of one conducting period of the device is followed almost immediately by the application between the anode and cathode of a potential favoring the renewal of conduction, a control grid between the anode and cathode, means for applying to the control grid a cyclically variable potential so phased as to inhibit renewal of conduction by the device during predetermined intervals, and means for fixing the potential distribution between the control grid and the anode to facilitate

the desired functioning of the former, said last-named means including a pair of intermediate electrodes, a potential divider for fixing the relationship between the potential of one of said electrodes and the potentials of the anode and cathode, and a source of cyclically variable voltage for rendering the one of said electrodes nearer the anode negative with respect to the other during the said predetermined intervals and positive with respect to such other electrode during periods of 10 desired conduction of the discharge device. 5

KENNETH H. KINGDON.
